(57) **CLAIM**

The ornamental design for an actuating-arm drive of a furniture flap, as shown and described.

DESCRIPTION

1. Actuating-arm drive of a furniture flap

1.1 : Front top and left perspective view

1.2 : Top

1.3 : Front

1.4 : Bottom

1.5 : Back

1.6 : Left

1.7 : Right

The broken lines in the drawings and the areas within them depict portions of the actuating-arm drive of a furniture flap that form no part of the claimed design.

1 Claim, 7 Drawing Sheets
